Be it known that I, CHARLES MAGEE, of Williamsburg, in the county of Kings and State of New York, have invented a new and original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

The figure K is a stripe containing ornamentation composed of a series of small irregular crosses.

The figure B is a stripe containing ornamental figures m, composed of circular flowers set on stems, and occurring at regular intervals, separated by small leafy branches, containing also figures l, somewhat resembling the figures m, and each composed of three flowers set on their stems.

The figure j is a stripe containing figures resembling a series of V-shaped figures, and having along one edge a series of regular pendant figures.

The stripe A contains an ornamentation consisting of the rosette-shaped figure e, having projecting therefrom the figure b, consisting of branches with buds and flowers thereon, and from this figure b, in turn, projects the flower-like figure f. The stripe A also contains the figure g, consisting of angular branches, connected with the figure b, and from this figure g projects the branch c, having a regular flower extending on each side thereof, this branch c bearing upon its end the open flower-like figure h. These various figures are repeated throughout the stripe A.

The stripe a is ornamented by a series of figures resembling arrow-heads set in regular order.
